CLAIM

The ornamental design for a sampling tool, as shown and described.

DESCRIPTION

FIG. 1 is a front isometric view of a sampling tool showing my new design;

FIG. 2 is a front elevational view thereof;

FIG. 3 is a right side elevational view thereof;

FIG. 4 is an enlarged cross-sectional view taken along line 4-4 of FIG. 2 thereof;

FIG. 5 is an enlarged top plan view thereof; and,

FIG. 6 is an enlarged bottom plan view thereof.

The enlarged rear elevational view is identical to FIG. 2; and The enlarged left side elevational view is identical to FIG. 3. The portions of the drawings depicted in broken dash lines represent the bounds of the claim and form no part of the claimed design. As to the broken lines denoting the bounds of the claim, neither the lines themselves, nor the region within said lines, form any part of the claimed design.

1 Claim, 1 Drawing Sheet
